(57) **CLAIM**

The ornamental design for a three slot cruciform catheter section, as shown and described.

DESCRIPTION

FIG. 1 is a front elevational view of a three slot cruciform catheter section, an adjacent catheter section being shown in phantom, the rear elevational view being a mirror image thereof;

FIG. 2 is a right side elevational view thereof, the left side elevational view being identical thereto;

FIG. 3 is a top plan view thereof; and,

FIG. 4 is a bottom plan view thereof.

The phantom lines in the drawings indicate environmental structure which forms no part of the claimed design.
